UNITED STATES PATENT OFFICE.

FRANK L. DIETZ, OF BROOKLYN, NEW YORK.

FUEL OIL.

No Drawing.

Application filed January 3, 1922. Serial No. 526,656.

This invention relates to fuel oils and it particularly relates to that class of fuel oil which is used in internal combustion engines for the production of motive power, the object of the invention being to produce a greater amount of energy per unit of weight or volume and to produce a fuel which will fill the highest requirements as to readiness to ignite and the precision with which these phenomena take place.

In my application filed November 16, 1921, under Serial No. 515,570, I have described a fuel oil which contains as chief material the socalled low temperature tar obtained by the dry distillation of coal at a temperature ranging from approximately 400-600 centigrade, or by gasifying coal in the gas producer having for instance a compartment or other suitable arrangement in which the coal is gasified at a low temperature before it actually enters the partial combustion process in the gas producer, to this low temperature tar being furthermore added an alcohol and a hydrocarbon miscible with such alcohol. As example of such a fuel oil formed by substances of the kind specified above I named a mixture of the following composition: 1 part low temperature tar, 1 part benzene, 1 part low temperature tar. I have now found out that I can substitute benzene or its equivalents specified in above patent specification by naphthalene-tetrahydride which is distinguished by several other merits as a fuel oil which one does not find with the various grades and kinds of hydrocarbons commonly applied as a motor fuel; for instance it develops an even pressure upon the piston during the combustion period and as it readily ignites the utilization of this hydride leaves the motor free of any knocks.

As naphthalene-tetrahydride shares this pleasant behavior with the low temperature tar it is an excellent material to be blended with components of a motor fuel. I want to state though that the price of this hydride is almost prohibitive for most of them at present, but in regard to naphthalenetetrahydride, which is already now of relatively low price and which was first made by Graebe, Bamberger, etc., I know that same in the near future will be ren-

dered available at such attractively low prices as to successfully compete with the other fuel oils also for this reason and not only upon the basis of superiority of a higher mileage per unit of volume or weight of fuel oil.

Inasmuch as the low temperature tar oil is greatly inclined to solidify owing to polymerization, or oxidation, owing to a certain content of unsaturated hydrocarbons as well as of phenols which display the same peculiarities when exposed to heat or air, I supply an agent which militates against this solidification; such antisolidification agents I have found to be the alcohols, for instance ethyl alcohol.

For the better illustration of my invention I cite various examples of the proportions in which I preferably mix these various ingredients together, the parts being on the basis of volume:

Example.—35 parts of low temperature tar, 30 parts naphthalene-tetrahydride, 35 parts of ethyl alcohol.

The low temperature tar resembles somewhat to the Caucasian crude petroleum as far as its hydrocarbon part is concerned and as the hydrides of the benzene hydrocarbons occur in such Caucasian petroleum in small quantities, any such hydride occurring in low temperature tar is not counted in aforesaid proportions. Whenever I speak in the claims of "benzene" hydrocarbons I mean to embrace such hydrocarbons which either have one, or several benzene rings condensed in its molecule.

What I claim is:

1. A fuel oil for the generation of power in explosion engines, consisting of low temperature tar, an alcohol acting as agent to prevent the solidification of such low temperature tar, and of naphthalenetetrahydride.

2. A fuel oil for the generation of power in explosion engines, consisting of low temperature tar, ethyl alcohol and naphthalene-tetrahydride.

In testimony whereof, I have signed my name to this specification this 28th day of November, 1921.

FRANK L. DIETZ.
